UNITED STATES PATENT OFFICE.

CARL WEEKS, OF DES MOINES, IOWA.

DESIGN FOR A PERFUME BOTTLE.

Application filed June 5, 1922. Serial No. 2,532. Term of patent 14 years.

To all whom it may concern:

Be it known that I, CARL WEEKS, a citizen of the United States, and a resident of Des Moines, in the county of Polk and State of Iowa, have invented a certain new, original, and ornamental Design for a Perfume Bottle, of which the following is a specification, reference being had to the accompanying drawing, forming part thereof.

I claim:

The ornamental design for a perfume bottle, as shown.

Des Moines, Iowa, May 15, 1922.

CARL WEEKS.
